UNITED STATES PATENT OFFICE.

JULIUS PROEGER, OF PITTSBURG, PENNSYLVANIA, ASSIGNOR TO MCKEE & BROTHERS, OF SAME PLACE.

DESIGN FOR TABLE-WARE.

SPECIFICATION forming part of Design No. 17,675, dated August 30, 1887.

Application filed July 13, 1887. Serial No. 244,933. Term of patent 7 years.

To all whom it may concern:

Be it known that I, JULIUS PROEGER, of the city of Pittsburg, in the county of Allegheny and State of Pennsylvania, have invented a new, original, and useful Design for Table-Ware; and I do hereby declare the following to be a full, clear, and exact description thereof.

My design is shown in the accompanying drawings, wherein Figure 1 is a side view of a vessel of table-ware embodying the design, and Fig. 2 is a vertical cross section on the line $x-x$ of Fig. 1.

Like symbols of reference indicate like parts.

The leading feature of the design consists in a vessel having projecting bosses with curved faces on its inner or outer surface, which bosses are provided with raised or sunken figures. The vessel shown in the draw-

ings has superficial bosses or projections 2, 20 with curved faces, which are ornamented with a prismatic figure, 3. On the upper part or body of the vessel the bosses are shown as on the outer surface, and at the base of the vessel they are shown as on the inner surface. The 25 effect is substantially the same in either case.

I claim—

The design for vessels herein shown and described, the same consisting in a vessel having superficial bosses with curved faces which 30 are provided with a raised or sunken figure.

In testimony whereof I have hereunto set my hand this 11th day of July, A. D. 1887.

JULIUS PROEGER.
